Thomas Edward King,
Inventor

By Macdonald & Macdonald,

Attorneys

UNITED STATES PATENT OFFICE.

THOMAS EDWARD KING, OF WESTFIELD, NEW JERSEY, ASSIGNOR TO HITCHINGS & COMPANY, OF ELIZABETH, NEW JERSEY, A CORPORATION OF NEW JERSEY.

GREENHOUSE.

Application filed September 29, 1927. Serial No. 222,779.

The subject-matter of the present invention relates generally to improvements in roof constructions for glazed buildings, such as greenhouses or conservatories and the like.

One of the features of the invention resides in the provision of means for supporting the sash-bars, which in turn carry the covering elements of the roof.

10 In one of the examples of the invention illustratively presented in the drawings, there is shown a sash-bar, channel-like in cross-section, the same being constructed of relatively thin material, so that the sides of 15 said bar may flex and accommodate the lateral movements of the covering elements. It is therefore essential that the means for supporting the sash-bars themselves shall possess the faculty of accommodating the 20 longitudinal movements of the same and at the same time permit the lateral movements of said sash-bars.

To this end my improved supporting means comprises a resilient member, substantially inverted U-shaped in cross-section, having somewhat elongated leg portions secured to certain of the structural elements of the roof, the stringers, for instance, and having the channel-like sash-bars rockably engaged by the bight portions of the supporting means, for a purpose to be presently pointed out.

In the accompanying drawing, a practical example of the invention is shown, wherein: 25 Figure 1 is a sectional detail of a portion of the roof structure embodying the invention.

Figure 2 is a transverse sectional view taken on the line 2—2 of Figure 1, the same 40 being slightly enlarged.

Figure 3 is a sectional view taken substantially on the plane of the line 3—3 of Figure 2, to illustrate the means for connecting the sash-bars to the tops or bight portions of the supporting means; and

45 Figure 4 is a view like unto Figure 2 but illustrating a slight change in form.

Referring now more specifically to the accompanying drawing, wherein like characters of reference denote similar parts throughout the several views, let 5 denote the rafters of a roof structure, the same being connected by a plurality of transverse stringers 6 and bridging the spaces there- 50 between.

Positioned above said rafters and disposed parallelly therewith, are a plurality of channel-like sash-bars 7, the same having lateral flanges 8 to support the covering elements 9 of the structure.

The means for supporting said sash-bars 7 comprises the members 10, substantially inverted U-shaped in cross-section and presenting elongated leg portions 11 having their extremities abutting each of the stringers 6 and secured to the lower leg thereof by means of the fastening means 12 and angle-irons 13, as clearly shown in Figure 2. The upper end or bight portion 14 of each of said members 10 is formed to seat within the upper portion of said sash-bars 7, and is secured thereto by means of bolts 17, passing through apertures 18. Thus longitudinal movements of the sash-bars are accommodated by a slight rocking on said members 10. However, under some conditions the lateral deflection of said sash-bars is somewhat pronounced, due to the expansion of the covering elements 9, and this condition being greater adjacent the area 70 contacted by said elements 9, I propose to bow inwardly the leg portions 11 of said members 10, as indicated at 15, and thus the movements of the sash-bars are accommodated. Any abnormal expansion of the 75 covering elements and attendant deflection of the sash-bars may be compensated in view of the resiliency of said members 10.

In the form shown in Figure 4, the bight portion 14 of said members 10 engages the inner portion of said sash-bars 7, yet the engagement is not snug enough to prevent movements between the parts when said sash-bar expands or contracts longitudinally.

From the foregoing it is apparent that I 95 have developed a structure exceedingly simple in construction, yet possessing sufficient rigidity to withstand the weight of the covering elements, and having inherent resilient qualities to accommodate the movements of both covering elements and sash-bars.

While the disclosure covers the preferred embodiment of the invention, it is to be understood that minor changes and alterations 105 may be resorted to liberally without departing from the spirit of the invention as defined in the appended claims.

I claim:

1. In a roof construction, in combination 110

with the framework including stringers and covering elements, resilient channel-like sash-bars for supporting said covering elements and adapted to absorb the expansion of said elements, and resilient channel-like means for supporting said sash-bars.

2. In a roof construction, in combination with stringers and covering elements, resilient channel-like sash-bars for supporting said covering elements, and resilient means substantially inverted U-shaped in cross-section connected to said stringers and supporting said sash-bars, said means presenting bowed portions to accommodate the lateral flexing of said sash-bars.

3. In a roof construction, in combination with stringers and covering elements, resilient channel-like sash-bars for supporting said covering elements and channel members for supporting said sash-bars, said members being substantially inverted U-shaped in cross-section, the bight portion thereof loosely abutting said sash-bars and the leg portions being rigidly connected to said

stringers, and said leg portions being bowed adjacent the lower portions of said sash-bars to accommodate the lateral movements thereof.

4. In a roof construction including stringers and channel-like sash-bars for supporting covering elements, resilient means for supporting a sash-bar and a stringer, said means being substantially inverted U-shaped in cross-section and presenting bowed portions to accommodate the lateral flexing of a sash-bar.

5. In a roof construction including stringers and channel-like sash-bars for supporting covering elements, means for connecting a sash-bar and a stringer, said means being substantially inverted U-shaped in cross-section, the bight portion thereof loosely abutting a sash-bar, and the leg portions being rigidly connected to a stringer, each of said leg portions being adapted to flex to accommodate the lateral movements of a sash-bar.

T. EDWARD KING.
